UNITED STATES PATENT OFFICE

HOSEA F. MAXIM, OF NORFOLK, VIRGINIA

CONNECTOR FOR ELECTRIC CONDUCTORS.

1,209,604.

Specification of Letters Patent.

Patented Dec. 19, 1916.

Application filed October 28, 1914. Serial No. 869,047.

To all whom it may concern:

Be it known that I, HOSEA F. MAXIM, a citizen of the United States, residing at Norfolk, in the county of Norfolk and State of Virginia, have invented certain new and useful Improvements in Connectors for Electric Conductors, of which the following is a specification, reference being had thereto to the accompanying drawing.

10 The object of the invention is to provide a wire connector which can be fastened in place, as, for example, to a battery cell, and which will have powerfully acting elastic wire gripping elements, which, however, can be opened by the application of pressure to the movable element without any strain being exerted at such time upon the fastener.

The invention can be embodied in a number of different forms of connectors and in 20 the accompanying drawing several such forms have been shown for purposes of illustration. It will be understood, however, that the invention is not limited to the forms shown and that others within the scope of 25 the appended claims are to be considered as coming within the spirit of the invention.

Of the drawings, Figure 1 is a perspective view showing the top part of a dry battery cell having attached to it two connectors embodying the invention. Fig. 2 is a perspective view of a modified form of connector embodying the invention. Fig. 3 is a perspective view of another modified form of connector embodying the invention. Fig. 4 is a perspective view of another modified form of connector embodying the invention. Fig. 5 is a perspective view of another modified form of connector embodying the invention.

40 Referring to the drawings, 1 represents as a whole a dry battery, the said battery having the zinc shell 2 and the central carbon terminal 3. These can be of any form as they of themselves constitute no part of my present invention. Attached to the zinc shell 2 and to the carbon terminal 3 are connectors 4 which are similar. A detailed description of one of them will suffice.

The connector 4 is formed of a single integral piece of wire and it consists of the coil 5 or coils, as at 5, 5^b from one side of which there extends the conductor engaging arm 6. The wire forming the arm 6 is doubled back upon itself so as to provide the 55 two bars or parts 7 and 8, which are spaced apart a distance about equal to the diameter

of the wire. Preferably the part 8 is provided with means for holding it in approximate parallelism with the part 7. In the preferred form, as shown, this means consists of the pivot 9 which is formed at the end of the part 8 and extends into the coil 5 and abuts against the lower inner surface thereof.

The wire extending from the other side of the coil 5 is formed near its end into a hook 10 which is positioned so as to project into, or, at least, lie in register with the space in the arm 6 between the parts thereof, 7 and 8. Preferably, though not necessarily, there is 70 also formed a second hook 11 similar to and in parallelism with the hook 10 and adapted to lie on the outside of one of the parts 7 or 8, as, for instance, the part 7 as shown.

The wire is bent to provide a means for 75 attaching the connector to the device which carries it and preferably this connecting means is formed between the coil 5 and the hook 10. As illustrated by the connector attached to the zinc shell, the attaching means 80 is in the form of a U 12, the legs 13 and 14 of which extend downward from the coil 5 and from the hook 10, respectively. As illustrated by the connector attached to the carbon terminal of the battery, the U 85 projects horizontally from the coil and the hook instead of downward.

The arm 13 which extends upward from the fastener 12 to provide the hook 10 is extended beyond the hook, and the free end 90 part of the wire is bent, as shown, to provide an abutment 15 adapted either to be engaged by the thumb or finger of the hand or to bear against a stationary object, as the top or side of a cell wall, at the time when pressure 95 is being exerted downward or inward on the arm 6. In either case the solder, screw, or the like, used for securing the fastener 12 in place, is relieved of strain or twisting when the arm 6 is pressed downward or inward to 100 release or connect a conductor.

In use the connector is attached as shown by means of the connecting U 12 to the zinc shell or the carbon terminal of the battery. When the conductor wire is to be inserted, 105 the arm 6 is depressed so as to cause the hook 10, and the hook 11 if provided, to project above it. Then the wire is inserted through the hooks above the arm and the arm is released. The spring force of the coil 5 throws 110 the arm upward against the conductor and the connector is thus pressed firmly against

the hooks, electrical contact in this way being established and maintained. The position of the attaching means 12 between the coil 5 and the hook 10 is highly advantageous as in this way it is positioned closely adjacent to both of the points of stress, namely, the coil 5 when down pressure is exerted on the arm, and the hook 10 when the arm is released and the wire gripped and afterward tensioned. The pivot 9, or equivalent device, for supporting the part 8 of the arm is important as it holds the part 8 in parallelism with the part 7. It will be clear that if the part 8 were left unsupported at its end, the said unsupported end would be forced downward relatively when contact was made with the conductor, thus making the grip upon the conductor relatively weak. The pivot 9, because of its engagement with the coil, serves to prevent any downward movement of the part 8 independently of the part 7.

It will be observed that the connector which I have provided not only has the numerous functional advantages which I have referred to, but also has the highly important advantage that it can be easily and cheaply manufactured. It consists of a single piece of metal, namely, a wire, and this wire can be made into the connector by simple bending operations, no others being required.

In Fig. 2 I have shown another form of connector which is very similar to that shown in Fig. 1, the principal difference being that in Fig. 2 the supplemental hook 11 is omitted. As stated, this supplemental hook is desirable under some circumstances but under other circumstances it is not needed and can be omitted, as shown in Fig. 2.

In Fig. 3 I have shown another connector also similar to the connector shown in Fig. 1 and differing from the said connector principally in that it has merely a single loop at 5 instead of a complete coil. The coil is preferable as it gives increased resiliency, but, under some circumstances, it can be omitted and the connector made in the form shown in Fig. 3.

In Fig. 4 I have shown still another connector which is also similar to the connector shown in Fig. 1. In this case the connector differs principally from the connector shown in Fig. 1 in that the pivot or abutment member 9^a contacts with the upper surface of the section 7 instead of with the coil. I prefer the construction shown in Fig. 1, but the construction shown in Fig. 4 can be used, if desired.

In Fig. 5 another connector is shown which is different in a number of respects from that shown in Fig. 1. Instead of the arm 6 having two parallel parts, there is provided an arm 6^a having at its end a coil with several loops 7^a and 8^a. The hook 10 is positioned to project between two of these

loops. At the end of the loop 8^a there is provided a transverse element 8^b adapted to pass through the hook 10 and limit the upward movement of the arm 6^a. It will be seen that when the arm 6^a is depressed, a conductor wire can be inserted through the loops 7^a and 8^a of the coil and through the hook 10. Then when the arm 6^a is released, the conductor will be caught by the loops 7^a and 8^a and forced upward against the hook.

In Fig. 6 there is shown still another connector. This connector differs principally from that shown in Fig. 2 by the provision of the attaching means 12^a beyond the hook 10 instead of between the hook and the coil. As stated before, I consider it highly advantageous to place the attaching means between the hook and the coil as then it is better adapted to carry the stresses. But under some circumstances it is possible to locate the connecting means as shown in Fig. 6, and I consider such a device as coming within the scope of my invention.

What I claim is:

1. A connector for electric conductors consisting of a single integral piece of wire formed into a coil, the wire at one side of the coil being doubled back upon itself to form a two part conductor engaging arm and being provided at the end with a pivot extending into and abutting against the coil, and the wire at the other side of the coil being bent to form a conductor engaging hook positioned to project between the parts of the arm when the latter is depressed against the spring action of the coil.

2. A conductor connector formed of a single wire bent upon itself to form one or more approximately closed coils, the wire from one side of the coils being bent to form a vibratable arm 6 with two bars 7 and 8 parallel and close together, the terminal bar 8 engaging with the coil to maintain parallelism with the bar 7 and the wire from the other side of the coils being extended outwardly approximately radially to form a fastener 12 having two parallel legs 13, 14, the leg 13 being positioned to extend between the bars 7 and 8 and turned outward to form a hook with an abutment at 15.

3. A conductor connector formed of a single wire having a fastener 12 with two or more parallel legs 13, 14, the leg 13 terminating in one or more approximately closed coils from which the wire is carried outward to form a vibratable arm 6 with two bars 7 and 8 close together and the end of one of the bars being arranged to bear upon the coils to maintain parallelism of the bars, and the leg 14 of the fastener being bent to provide both a wire holding loop 10, and an abutment at the end of the wire to take the strain when pressure is applied to the vibrating arm 6.

4. A conductor connector formed of a single piece of wire having both of its ends free,

one end being formed with an abutment 15 and a hook loop 10, the other end part of the wire being shaped to form a vibrating arm 6 with two closely adjacent parallel bars 7 and 8, the central part of the wire between the said vibrating arm and the said loop hook being bent to form a fastener next to the hook and to form one or more approxi-

mately closed spring coils between the fastener and the vibrating arm.

In testimony whereof, I affix my signature, in presence of two witnesses.

HOSEA F. MAXIM.
